UNITED STATES PATENT OFFICE

2,500,554

MEANS FOR THE PERMANENT WAVING
OF HAIRWilliam MacDonald and Hugh MacDonald,
Inverness, ScotlandApplication January 28, 1948, Serial No. 4,894
In Great Britain October 4, 1946Section 1, Public Law 690, August 8, 1946
Patent expires October 4, 1966

5 Claims. (Cl. 219—24)

1

This invention relates to means or devices for use in the so-called permanent waving of hair (which includes imparting a permanent set or removing internal stress or curl) and is more particularly concerned with heat jacketing means of the kind employing electric current as the heat supplying medium or agent.

Various means or devices involving rigid containers or jackets wired with the electric heating resistances are known, and a flexible sachet containing chemicals which develop heat on the application of moisture and which is adapted to be folded or wrapped about the curler or mandrel is also known.

The present invention has for its object an improved heat applying device of the electric type which is light, and adapted to provide intimate enclosure of the hair upon the curler or mandrel when operating at low temperatures up to about 60° C., as employed in what may be termed a "low temperature" waving process or system carried out by the aid of special chemicals which enable a satisfactory waving treatment to be followed without the use of elevated temperature such as employed in systems of permanent hair waving in use today. The invention is particularly suitable for use in carrying out the "low temperature" permanent hair waving processes as described in British Patents Nos. 453,700, 453,701, and 456 336.

The invention is applicable to treatments in which the hair is rolled upon the curler either from the root towards the point or vice versa.

The invention consists in an electric heating device of the kind indicated comprising a pad or jacket of a foldable or flexible material embodying or containing flexible electrical resistance wiring and adapted to be folded or wrapped about a hair waving curler or mandrel, and preferably with releasable means for retaining the pad or jacket in the folded or wrapped position upon the curler or mandrel.

The invention also comprises a device as indicated in the preceding paragraph, wherein the pad is in the form of an envelope or flat bag and electrical resistance wiring is carried by or within a flexible support inserted in the envelope.

According to one form when the hair is wound on to the curlers from root to point, the pad or jacket and the enclosed resistance support is recessed at one end to accommodate that part of a tress of hair between the wound portion and the roots.

The resistance wiring or convolutions thereof may be arranged or distributed in any suitable manner to give uniform heat over the length of

2

wound hair or to prevent a temperature gradient towards either end of the curler or mandrel or either side of the heating pad, or the resistance wiring may be spaced or grouped to afford more heat in a certain locality (or localities) than elsewhere.

The pad or jacket may be moisture-proof flexible material such as rubber sheet, rubberised cloth, a synthetic rubber sheet or cloth treated with synthetic rubber or a plastic impregnated fabric. Insulation covered resistance wire may be employed or the resistance wire may be insulated by enclosing it between layers of insulating material.

15 Referring to the accompanying drawings:

Figure 1 is a perspective view of a heating pad or jacket constructed in accordance with the invention, the flap of the covering envelope being shown open and portions cut away to show the

20 internal construction;

Figure 2 is a side view of the pad or jacket ready for use;

Figure 3 is a side view of the resistance element of a heating pad or jacket;

25 Figure 4 is a side view of an alternative form of heating element;

Figure 5 is a side view of an alternative form of heating pad or jacket embodying the heating element shown in Figure 4;

30 Figure 6 is a perspective view showing a heating pad in position upon a hair curler;

Figure 7 is an end view of the above;

Figure 8 is a perspective view of a pad of the form shown in Figure 2 in position on a curler;

35 Figure 9 is a side view of a further modified form of heating element.

In carrying the invention into effect according to one convenient mode as described by way of example, a series of pads or jackets are manufactured each of which comprises a flat bag of rectangular shape, say 2½ inches by 1¼ inches, or 3¾ inches by 2 inches, although these dimensions are not limiting factors. The bag comprises an outer envelope 1 (Figure 1) of rubber or other

40 flexible material having a flap 2, within which is a similar envelope 3 the flap 4 of which is sealed. Within this again an envelope of material such as that known under the registered trade mark cellophane encloses the resistance element 6. As shown in greater detail in Figure 3, the resistance element comprises two layers of cotton or other textile fabric which are placed together and stitched longitudinally as at 9 to form a row of parallel channels through which the resistance 45 wire 3 is threaded in a series of loops, to the ends

of which the insulated leads 10, 11 are attached. The element so formed is enclosed within an envelope of cellophane or similar material as referred to above, the edges being adhesively secured. The flap 2 of the outer bag is tucked in as shown in Figure 2 and a pair of rubber bands 13 may be slipped lengthwise over the bag for additional security. The outer bag can thus be readily changed on becoming soiled or worn. It should be noted that in Figure 1 the thickness of the pad is shown to an exaggerated scale for the sake of clearness.

An alternative form of heating pad or jacket is shown in Figures 4 and 5. The fabric base 14 of the resistance element is provided with a recess 15 at one end and the resistance wiring 16 is stitched on to form three groups of convolutions so that more heat is afforded at the ends of the pad than at the central portion.

The element is enclosed within two bags of rubber or like material one within the other as described in the previous example, each of which is provided with a recess 18 at one end as shown in Figure 5. The flap of the outer bag is tucked in and a rubber band 19 is applied lengthwise outside the bag. The purpose of the recess 18 is to accommodate that part of a tress of hair between the wound portion and the roots, and with a view to including the adjacent hair wound upon the end of the mandrel more conveniently within or under a part of the resistance, as will hereinafter be explained.

Another modified form of heating element is shown in Figure 9, the resistance wire being stitched on to a fabric base in the disposition illustrated, and enclosed in an envelope of cellulosic material as previously described. This arrangement is provided to prevent temperature gradients towards the sides of the heating pad which are found to occur in certain circumstances.

The heating pads or jackets with their contained resistances as described above may be manufactured and electrically connected in series to a common plug-in terminal or the like. Groups of four or more pads are suitable or a range of groups may be provided and individual pads may also be supplied for the purpose of making up any desired number according to the number of tresses to be treated.

One method of applying the heating pad in the hair waving treatment is illustrated in Figures 6 and 7. The tress of hair 29 is passed through a rubber washer 21 and wound in the direction root to point upon any suitable form of curler 22. The hair may be covered by a sachet or impregnated cloth, or may be damped with a treating solution or mixture, and the damped or covered hair is then preferably enclosed in a thin flexible tube, envelope, or wrapping of any suitable material, such as that known by the registered trade mark "cellophane," or other suitable thin plastic membrane. The pad or jacket 23, of the form shown in Figure 5, is then folded over the enclosed hair on the curler so that the two longer edges lie adjacent one another and the root part 24 of the tress occupies the recess 18 (Figure 5). In this position a clip 25 is applied over the curler and folded part of the pad to keep it in position and snugly press the folded part around the tress of hair. A suitable clip as illustrated is one of the hinge spring type such as employed for clipping papers together provided with semi-cylindrical or like embracing jaws 26 having rods 27 fixed thereto.

Having applied heating pads to all the curlers in the manner described above, current is switched on to the heating elements which may be plugged into sockets upon or carried by a master flexible lead or manifold extending from a variable transformer which may be supplied with current from any convenient mains source. The output side of the transformer may be provided with a limit switch and/or with a time switch device such that after the current has been switched on by the operator the current is cut off automatically after a predetermined time, according to that required for the permanent hair waving operation.

Alternatively there may be independent controls for certain of the heating pads or groups thereof so that a longer treatment may be given to certain of the hair tresses than others.

Another method of applying the heating pad where the waving is to be effected by rolling the hair from the point towards the root upon the curler is illustrated in Figure 8. The hair is wound upon a mandrel or curler 28 which may be of wood or other similar material, and is secured by a cord 29, the free end of which is anchored by being wedged in a slot 30 at one end of the mandrel. The hair is then treated or damped, or a sachet or the like applied, and enclosed by a thin wrapping as previously described, after which a heating pad which may be of the form shown in Figure 2 is folded over the curler and secured by a clip 32, the heating current then being switched on as described.

It will be understood from a consideration of the foregoing examples that heating pads or jackets according to the invention may be applied to many different forms of hair curler.

Various forms of clip may be employed and if desired the jaw portions or other parts, excepting the spring, may be made of plastic material such as that known by the registered trade mark "Bakelite." Instead of providing a mechanical clip for the folded or wrapped heating pad, the pad may be provided with tie means, such as tapes, or the pad may be secured by an elastic band or bands.

According to another alternative means for securing the jacket, an elastic band with a ring may be attached to the pad and a projection or hook arranged at the opposite end of the pad. After the pad has been folded over the curler the elastic band is stretched and the ring is slipped over the projection so that the pad is held in the folded position. In order to lend the jacket longitudinal stiffness against the action of the elastic band, the side or sides of the jacket may be reinforced with a stiffening pad or member.

We claim:

1. An electrically heated hair waving device having the form of a flexible sheet-like pad of elongated shape capable of being folded about a curled or wound tress of hair lying lengthwise of the pad to enclose the tress, and comprising a bag-like enclosure, a support for electrical resistance wiring disposed within said enclosure, resistance wiring arranged in loops upon said support with the loops more closely spaced near the ends of said support so as to afford a greater warming effect at the ends of the pad, and the sheet-like pad having at one end a recess open at one end and extending inwardly in the direction of the length thereof, the size of said recess being such that it can receive within it that part of a tress of hair between the curled or wound portion and the hair roots and thereby

ensure that the wound part of the tress is completely enclosed within the uniformly heated region of the pad.

2. An electrically heated hair waving device according to claim 1, comprising a pad of substantially rectangular form having a recess also of substantially rectangular form extending inwardly from one end thereof and with the sides of the recess substantially parallel with the longer sides of the pad.

3. An electrically heated hair waving device having the form of a flexible sheet-like pad of elongated shape capable of being folded about a curled or wound tress of hair lying lengthwise of the pad to enclose said tress, and comprising a bag-like enclosure, a support for electrical resistance wiring disposed within said enclosure, resistance wiring arranged in loops upon said support with the loops more closely spaced near the ends of said support so as to afford a greater warming effect at the ends of the pad, the sheet-like pad having at one end a recess open at one end and extending inwardly from the end of the pad and between the longer sides thereof, the resistance wiring being arranged so that it lies on at least one side of said recess, and the size of the recess being such that it can receive within it that part of a tress of hair between the curled or wound portion and the hair roots and thereby ensure that the wound part of the tress is completely enclosed within the uniformly heated region of the pad.

4. An electrically heated hair waving device according to claim 3, in which the said recess

lies nearer to one of the longer sides of the pad than to the other, and the resistance wiring is arranged so that it lies at least on that side of the recess which is furthest from the said longer side.

5. An electrically heated hair waving device according to claim 3, in which the resistance wiring is arranged so that it lies on both sides of the said recess to afford uniform heating of the wound or curled tress of hair in the neighbourhood of the recess.
